DISPENSING DEVICE

William M. Venable, Pittsburgh, Pa., assignor to
 Blaw-Knox Company, Pittsburgh, Pa., a corporation of New Jersey

Application March 24, 1938, Serial No. 197,839

6 Claims. (Cl. 184—7)

This invention relates to a dispensing device and, in particular, to a device for use in centralized lubricating systems to dispense fluid or semi-fluid materials such as lubricants.

- 5 The invention operates on a principle similar to that of known devices wherein the delivery of material under pressure to an inlet effects a dispensing operation, fills a measuring chamber and, on release of the pressure on the material, causes 10 the measured amount to flow from the measuring chamber to a position ahead of a discharge piston for subsequent dispensing. Devices of this kind which have been known heretofore have been characterized by relatively large size and some- 15 what costly construction. It is an object of this invention to improve upon such devices by providing a compact dispenser which can be manufactured at relatively low cost.

According to the invention, a dispenser includ- 20 ing a cylinder and a piston reciprocable therein is adapted for operation as above explained by the provision of a control valve and connecting passages in the discharge piston itself. In a preferred form, a piston reciprocable in a cylinder 25 has an axial bore in which a piston valve is movable. Passages intersecting the bore permit material delivered to an inlet communicating with the cylinder to flow into the space behind the piston, thereby causing a discharge or eject- 30 ing stroke of the latter. When the pressure applied to the material is released, the piston valve is restored to its normal position thereby establishing a by-passing passage for the material forced into the cylinder behind the piston which 35 thereupon flows through the piston to the other side thereof and is then ready to be ejected on the next stroke. It will be understood that devices of the character to which the invention relates are operated only at intervals, depending 40 upon the lubricating demands of the machinery with which the device is associated. The bore in the piston is axial in one form of the invention and transverse in a modification. These forms are shown in the accompanying drawing in which:

45 Fig. 1 is a longitudinal central section showing the parts in their normal positions;

Fig. 2 is a similar view showing the parts in their measuring and discharging positions;

Fig. 3 is a similar view showing the parts in 50 their by-passing positions;

Fig. 4 is a similar view of a modification showing the parts in their normal positions; and

Fig. 5 is a transverse sectional view taken along the line V—V of Fig. 4, with the parts in the 55 dotted line positions.

Referring now in detail to the drawing, the device comprises a body 10 having a bore with piston 11 reciprocable therein. The ends of the bore are closed by plugs 12 and 13. The plug 12 has a hole therethrough and is adapted to receive 5 a connection 14 extending to the machine part or other apparatus to be lubricated. An adjusting screw 15 is threaded through the plug 13 and is provided with a lock nut 16.

The piston 11 has an axial bore 17 there- 10 through, one end of which is closed by a plug 18. A compression spring 19 bearing against the plug 12 and the piston 11 normally urges the latter to the right until the plug 18 engages the screw 15. A piston valve 20 is reciprocable in the bore 17 15 and is normally urged against the plug 18 by a compression spring 21. The spring 21 bears against a transverse pin 22 extending across the piston adjacent the open end thereof.

An inlet 23 communicating with the body 10 is 20 adapted to be connected to any convenient source of the material to be dispensed. An annular recess 24 formed in the piston communicates with the inlet in all positions of the piston. A passage 25 connects the recess 24 with the closed end of 25 the bore 17. A passage 26 extends inwardly from the end of the piston 11 and intersects the bore 17 at a point therein beyond the valve 20 when the latter is in the normal position.

The operation of the device will now be ex- 30 plained with reference to Figs. 2 and 3 illustrating the relative positions of the parts at successive stages of a complete operating cycle. When the parts are in the positions illustrated in solid lines in Fig. 1, material such as a semi-fluid lubricant 35 delivered under pressure to the inlet 23 fills the recess 24 and flows through the passage 25 into the bore 17 behind the piston valve 20. The latter is provided with a projecting stop portion 27 which insures ample clearance between the body 40 of the piston valve and the end of the bore to admit material behind the former. As the ma- 45 terial flows into the bore 17, the piston valve 20 is displaced from the position shown in solid lines to the dotted line position of Fig. 1. Such movement of the valve 20 uncovers the inter- 50 section of the passage 26 with the bore 17, permitting material to flow through the former into the bore in the body 10 behind the piston 11. The piston 11 is thus caused to effect a discharge 55 or ejecting stroke, as illustrated in Fig. 2, by the pressure of the material delivered into the right hand end of the body 10 in the manner already described. As will become apparent shortly, the end of the body 10 adjacent the discharge connec-

tion 14 is normally filled with the material being dispensed whereby the piston 11 is displaced from the left hand end of the body precisely the amount of material delivered into the right hand end thereof. The right hand end thus serves as a measuring chamber while the left hand end constitutes a storage chamber preparatory to a succeeding ejecting stroke of the piston 11.

The ejecting movement of the piston 11 is limited by the collapsed length of the spring 19 although any other suitable means may be employed for this purpose. Fig. 2 shows the relative positions of the parts when the piston 11 has reached the limit of its movement. When the piston has reached this position, the discharge of material through the connection 14 is terminated, even though pressure is maintained on the material entering the inlet 23. As soon as this pressure is relieved, however, the piston valve 20 is restored to its normal position relative to the piston 11 by the spring 21. The material displaced by the restoring movement of the piston valve flows outwardly through the passage 25 and inlet 23. The spring 21 must be strong enough relative to the force exerted by the spring 19 to restore the piston valve 20 to its limiting right hand position before the spring 19 is effective to restore the piston 11. As soon as the piston valve 20 has reached its limiting right hand position a direct by-pass is provided through the passage 26 and the bore 17 for the material behind the piston 11. The spring 19 is then effective to restore the piston 11 causing the material behind the piston to be displaced through the by-passing passage to the left hand end of the body 10 for discharge upon a subsequent operation. The positions of the parts during the restoring movement are as shown in Fig. 3. The screw 15 determines the initial position of the piston 11 and thereby controls the amount of material discharged at each operation of the device. Figs. 2 and 3 merely show how the recess 24 maintains communication with the inlet 23 in all positions of the piston 11.

Dispensing devices such as shown and described may be used in such numbers as required to deliver lubricant to various machine elements. A number of the devices may, therefore, conveniently be embodied in a unitary casting and may have a common connection to the lubricant supply with separate connections from each device to the element to be lubricated thereby.

A modified construction is shown in Figs. 4 and 5. This form includes a cylinder 30 having one closed end provided with a discharge connection 31. The other end of the cylinder is closed by a cover 32 having an adjusting screw 33 threaded therethrough corresponding to the screw 15. An inlet connection 34 communicates with an annular groove 35 formed in the wall of the cylinder.

A piston 36 is reciprocable in the cylinder and is normally maintained against the screw 33 by a spring 37. A passage 38 in the piston maintains communication with the inlet 34 in all positions of the piston.

A transverse bore 39 is formed in the piston and a piston valve 40 is reciprocable therein, being normally urged toward the retracted position shown in solid lines by a spring 41. As shown, the valve 40 normally overlies the port 42 connecting the bore 39 with the right hand end of the cylinder 30. A bore 43 through the

piston connects the opposite ends of the cylinder when the valve 40 is in its normal position.

The operation of the modification shown in Figs. 4 and 5 will probably be apparent from the description of the device shown in Fig. 1 but will be briefly reviewed. When material such as a semi-fluid lubricant is delivered through the inlet 34 under pressure, the piston valve 40 is first displaced to the dotted line 10 position to uncover the port 42 thereby admitting the material to the right hand end of the cylinder 30. This causes displacement of the piston 36 and any material which may previously have been fed into the left hand end of the cylinder, as the valve 40 closes the passage 43 when displaced. When the pressure on the material delivered to the inlet is relieved, the valve 40 is restored to its original retracted position opening the passage 43 and closing the port 42. Restoration of the piston 36 by the spring 37 is thereby made possible and the material in the right hand end of the cylinder is displaced through the former into the left hand end as the piston moves to the right until it engages the screw 33.

While the passage 38 in the piston has been illustrated in alignment with the inlet 34 it will be understood that communication between the former and the latter is maintained by the groove 35 regardless of angular movement of the piston within the cylinder.

It will be apparent from the foregoing description that the invention provides a simple and compact form of dispenser which is particularly adapted for the delivery of a measured amount of material such as a semi-fluid lubricant by the simple expedient of applying pressure to a supply of the material connected to the device. Both forms of the invention shown are very simple and compact and may be manufactured at relatively low cost since the parts are such as to require only the simplest machining operations. At the same time, the device is sturdy in design and characterized by a long, useful life without requiring any substantial maintenance or adjustment.

Although I have illustrated and described herein but a preferred form of the invention and a modification, changes in the structure shown may be made without departing from the spirit of the invention or the scope of the appended claims.

I claim:

1. A device for dispensing a measured quantity of material comprising a cylinder, a piston reciprocable therein, means normally urging said piston toward one end of said cylinder, a bore in said piston communicating with said cylinder and a piston valve reciprocable in said bore, means normally urging said valve toward one end of said bore, an inlet for said cylinder, a passage in said piston communicating with said inlet and with said bore at a point such that pressure applied to said inlet causes the piston valve to be displaced, and means providing a passage in said piston adapted on advance movement of said valve to admit material behind said piston to cause movement thereof in opposition to said first mentioned means, and on retraction of said valve, a passage to conduct material from behind said piston to said bore.

2. A device for dispensing a measured quantity of material comprising a cylinder, a piston reciprocable therein, effective on reciprocation to

5 displace material in the cylinder, means normally urging the piston toward one end of the cylinder, a bore in the piston and a valve therein, means normally urging the valve toward one end of the bore, an inlet for said cylinder, a passage in the piston communicating with said inlet and said bore in such manner that material under pressure delivered to said inlet displaces the valve, and passages in the piston adapted on displacement of the valve to admit material behind said piston and on retraction of the valve to by-pass material through the piston for a subsequent discharge thereby.

10 3. A dispensing device comprising a cylinder, a discharge port communicating with one end of the cylinder, the other end being closed, a piston reciprocable in said cylinder, means normally urging the piston toward the closed end of the cylinder, a bore in said piston, said bore being closed at one end thereof, the other end of the bore communicating with the cylinder, a piston valve in said bore, means normally urging the valve toward the closed end of the bore, an inlet communicating with said cylinder, a passage in said piston connecting said inlet with the closed end of said bore, and a passage in said piston connecting the closed end of the cylinder to said bore at a point beyond said valve when the valve is in normal position.

15 4. A dispensing device comprising a body having a bore therein, a discharge port communicating with one end of the bore, the other end being closed, a piston reciprocable in said bore, means normally urging the piston toward the closed end of the bore, a bore in said piston, said piston bore being closed at one end thereof, the other end of the piston bore communicating with the first-mentioned bore, a valve reciprocable in the bore in said piston, means normally urging the valve toward the closed end of the piston bore, an inlet communicating with said first-mentioned bore, a passage in said piston connecting said inlet with the closed end of said piston bore, and a passage in said piston connecting the closed

20 end of the first-mentioned bore to said piston bore at a point beyond said valve when the valve is in normal position.

5 5. A dispensing device comprising a body, a piston reciprocable in a bore in said body and effective on a forward stroke to deliver material disposed ahead of its forward face, under the pressure of material supplied behind its rear face, means normally urging said piston toward its retracted position, an inlet in said body communicating with said bore, a bore in said piston, a valve reciprocable in said piston bore, means for normally urging said valve toward one end of said piston bore, a passage in said piston connecting said inlet with said end of said piston bore, a second passage in the piston connecting the rear end of said first-mentioned bore with said piston bore at a point ahead of the valve when the latter is retracted to said end of its bore whereby material supplied to said inlet displaces the valve against the force exerted by said second-mentioned means, said passages being effective on displacement of the valve to admit material from said second-mentioned bore to the rear face of the piston and, on restoration of said valve to said end of its bore, to by-pass material from behind the rear face of the piston to the space ahead of the forward face.

10 6. Apparatus for dispensing a measured amount of fluid comprising a cylinder having an outlet adjacent one end, a piston reciprocable in said cylinder for discharging material by a forward stroke in the cylinder, means urging said piston toward a normal position near the rear end of the cylinder, an inlet in the side of the cylinder, a bore in said piston, a piston valve reciprocable in said bore, means normally urging said valve to a retracted position, means connecting said inlet to said bore whereby the pressure applied to fluid in the inlet is effective to displace the piston valve from its retracted position, means in said piston providing a passage connecting the inlet to the rear end of said cylinder which is closed by said valve in its retracted position, and means providing a by-passing passage through said piston which is closed when said valve is displaced.

15 25 30 35 40 45 WILLIAM M. VENABLE.
